UNITED STATES PATENT OFFICE.

EDWIN M. BROWN, OF ASHTABULA, OHIO.

TRAP-NEST.

No. 902,370.

Specification of Letters Patent.

Patented Oct. 27, 1908.

Application filed March 25, 1908. Serial No. 423,197.

To all whom it may concern:

Be it known that I, EDWIN M. BROWN, a citizen of the United States, residing at Ashtabula, in the county of Ashtabula and State of Ohio, have invented certain new and useful Improvements in Trap-Nests; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in trap nests and consists of means whereby a hen may automatically raise a pivotal trap which automatically locks when falling by gravity.

The invention comprises various details of construction, combinations and arrangements of parts which will be hereinafter fully described and then specifically defined in the appended claims.

My invention is illustrated in the accompanying drawings, in which:

Figure 1 is an elevation showing the trap set in readiness to be raised by a hen. Fig. 2 is a similar view showing the trap at its lowest limit and locked.

Reference now being had to the details of the drawings by letter, A designates the board of a nest and has an opening B therein. C is a door pivotally mounted upon a pivot D upon the board, and E is a stop upon the board to limit the downward throw of said door. The forward free edge of the door has a notch F formed therein, and G is a pivot pin mounted upon the board upon which pin a gravity pawl H is pivotally mounted. It will be noted that said pawl H is mounted at one side of its center and so arranged that, when tilted, the weighted end thereof will fall down and engage the notch F and hold the door locked.

In operation, the locking pawl is arranged as shown in Fig. 1 of the drawings so that the hen by putting its head through the

opening beneath the door and pushing up 50 lightly upon the door will cause the pawl to tilt and its weighted end will fall to the position shown in Fig. 2 of the drawings and engage the notch F when the door falls by gravity against the stop E, thereby locking 55 the door at its lowest throw. To set the door, the pawl is swung about upon its pivot to the position shown in solid lines in Fig. 1 in readiness to be again tilted by the raising 60 of the door.

In Fig. 2 of the drawings, I have shown in dotted lines the trap suspended above the opening so that the device may be utilized as an open nest. In said dotted lines, one end of the pawl is shown as engaging a recess O 65 formed in the end of the door.

From the foregoing, it will be noted that, by the provision of a door for nests as shown and described, a simple and efficient means is afforded which will allow a hen to raise 70 the door and pass through the opening, the door automatically locking as it falls by gravity.

What I claim to be new is:

In combination with an apertured board, 75 a trap door pivoted a short distance from the marginal edge of the opening in said board, a stop upon the latter to limit the downward throw of the door, the upper portion of the swinging end of the latter provided 80 with a shoulder, a pawl pivotally mounted at one side of its center upon said board and having two operative ends, one being heavier than the other, the heavier end of the pawl adapted to engage said shoulder to hold the 85 door upon said stop, said pawl being so mounted with respect to the door that the heavier end of the pawl will hold its opposite end against the door when the trap is set, as set forth.

In testimony whereof I hereunto affix my signature in the presence of two witnesses.

EDWIN M. ^{his} ~~mark~~ BROWN.
